UNITED STATES PATENT OFFICE.

CHRISTIAN CHASKEL EISENBERG, OF BERLIN, GERMANY.

MACHINE FOR FLANGING UPERS OF BOOTS OR SHOES.

SPECIFICATION forming part of Letters Patent No. 548,184, dated October 22, 1895.

Application filed February 28, 1895. Serial No. 539,433. (No model.)

To all whom it may concern:

Be it known that I, CHRISTIAN CHASKEL EISENBERG, of Berlin, Germany, have invented an Improvement in Machines for 5 Flanging the Uppers of Boots or Shoes, of which the following is a specification.

My improvement consists in a machine for forming a flange or rim around the uppers of boots and shoes of all kinds.

10 The object of my invention is to so construct a machine that a flange or rim may be readily and conveniently formed all around the lower edge of the upper of a boot or shoe; and it consists in certain details of construction which will be hereinafter fully described.

15 Referring to the drawings, forming a part of this specification, and on which like letters and numerals indicate corresponding parts, Figure 1 is a side elevation of the machine.

20 Fig. 2 is a top plan view thereof. Fig. 3 is a view similar to Fig. 1 with the working mechanism in a different position. Fig. 4 is a view corresponding with Fig. 2 with the working parts in a different position. Fig. 5 is a view

25 partly in section, taken on the line xx , Fig. 1. Figs. 6 and 7 are details to be hereinafter referred to.

C is a column or base on which is mounted the head-plate b , to which the vertical supports c are bolted or otherwise properly secured. (See Fig. 7.) On top of the supports

30 c is secured a plate d , having the general outline of the sole of a boot or shoe. This plate d is provided with a tenon 1, which en-

35 gages a hole or opening 2 in one of the standards c , and thus secures the plate d in position. Two arms or brackets 3 4 project outwardly at each side of the column or base c and support the right and left screw-threaded

40 rod or spindle 5. At each end of this rod or spindle 5 is a hand-wheel h for operating the same.

Two nuts i , one at each side of the machine, are provided, and each of the nuts car-

45 ries a plate 10, for a purpose which will be presently explained. The nuts i are tapped to engage with and be operated by the screw rod or spindle 5, and they are arranged to slide in ways in the top of the arms or brackets 3 4. (See Figs. 1 and 5.) To the plates

50 10 are secured pressure-plates 11, and the inner edges of these plates 11 are shaped to

conform to the shape of the shoe. The plates 11 are connected to the plates 10 and made so as to be readily detached from said plates by 55 means of a ball-and-socket connection on the plate 10 and nuts, and are held in place by means of slides 12, which are secured to the nuts so as to prevent the disengagement of the ball-and-socket connections unless it is 60 desired to remove the plates.

The plate b is provided at suitable points with a series of clamp fingers or tweezers g , which extend upwardly therefrom, and the jaws of these clamps may be opened or closed 65 by means of the thumb-screws 7, (see Fig. 6,) while the fingers or tweezers may be adjusted up or down and held in place by the wing or thumb-screws 6 on the lower ends of the clamp-rods, which preferably pass through 70 holes in the plate b and have the thumb-screws on the under side thereof.

The plate d , which supports the last, has preferably a circumferential groove in its edge to receive the edges of the plate 11. 75

A curved plate 14 the shape of the heel of the shoe is pivoted to one of the plates 11. It is provided with a handle for operating it and carries a toothed ratchet which engages with a pawl or pin on the other plate. A similar 80 plate 15, with its handle, pawl, and ratchet, is provided at the toe of the shoe or last.

Screw-rods 18 19, operated by thumb-nuts, may be used to bear against the plates 14 15, and springs may also be used to hold the 85 ratchets and pawls in engagement.

Instead of the mechanism just described for forming the flange or rim at the heel and toe, I sometimes duplicate the mechanism used for forming the side flanges—that is to say, another screw rod or spindle and two arms at right angles to the rod 5 and arms 3 and 4 would be used with the sliding nuts, plates, and other mechanism, the only change necessary being to form the plates the shape of the 95 heel and toe.

The operation of the machine is as follows, viz: When the pressure-plates 11 have been brought into the position shown in Fig. 3 by turning the hand-wheels, the last is secured 100 to the plate d , the upper mounted thereon and drawn down over the edge of the plate and clamped by the cheeks of the jaws or tweezers. When the edges of the upper have been

clamped at enough places, the nuts 6 are turned until the upper is stretched tight on the last. When this has been done, the slides 11 are brought closer together by revolving the screw rod or spindle and engaging with the upper at a point between the bottom of the last and the plate d, and this operation forms the flange or rim. The rim d' practically forms a groove with the plate and as the slides 11 are advanced hold the leather securely. The flange at the heel and toe is formed by means of the curved plates 14 15, operated by the handles in a manner that will be readily apparent. After these plates have been forced against the upper they may be still further advanced and the pressure thereby increased by operating the screws 18 19. In order that the shape thus given the upper may be retained, the upper, with the last and the parts 11, 14, and 15 are taken out of the machine and placed in a drying room or space. After the upper is completely dry and the flange or rim is permanent the screws connecting the plate and the last are removed and the latter is allowed to remain in the shoe until it is finished. I am thus enabled to avoid changing the last so often as in the usual manner and to preserve the shape of the shoe throughout the entire process of manufacture and not distort or disfigure the same, as in the common methods. Another advantage of the machine is that the whole operation is performed with the last right side up, so that the work being done is always in full view of the operator, which is not the case when the last is inverted, as in the old way, or, in other words, with the sole up.

Minor changes may be made in the details of construction without departing from the spirit or sacrificing any of the advantages of the invention and still be within the scope thereof.

Having thus fully described my invention, what I claim as new, and desire to secure by Letters Patent, is—

1. In a machine for flanging the uppers of boots and shoes, a supporting plate for the last, clamps or tweezers for drawing down the edge of the upper, sliding plates for flanging

the sides of the upper and mechanism for operating the same, separate plates for flanging the heel and toe, the last and flanging plates all being removable from the machine, substantially as described.

2. In a machine for flanging the uppers of boots and shoes, a supporting plate for the last, means for clamping the plate to the latter, a plate beneath the last provided with a series of clamps or tweezers for drawing down the upper, sliding plates for flanging the sides of the upper, a right and left screw for operating them, and separate plates for the heel and toe, and means for operating them, substantially as described.

3. In a machine for flanging the uppers of boots and shoes, a suitable support or stand, a right and left screw rod or spindle mounted thereon, and means for revolving it, tapped nuts carried by said rod, removable side flanging plates carried by the nuts, separate heel and toe flanging plates, means for operating them and locking them in closed position, and a supporting plate for the last, substantially as described.

4. In a machine for flanging the uppers of boots and shoes, a supporting plate for the last and means for clamping the latter thereto, side flanging plates and separate heel and toe flanging plates, all of which are removable from the machine, substantially as described.

5. In a machine for flanging the uppers of boots and shoes, a suitable support or stand, a right and left screw rod or spindle mounted thereon, means for operating it, tapped nuts carried by said rod, side flanging plates carried by the nuts, separate heel and toe flanging plates, levers or handles for operating them, screw rods or nuts for giving additional pressure, and a last supporting plate and last, substantially as described.

In witness whereof I have hereunto set my hand in presence of two witnesses.

CHRISTIAN CHASKEL EISENBERG.
